UNITED STATES PATENT OFFICE.

SIGMUND L. GOLDMAN, OF CHICAGO, ILLINOIS.

GAS-VENTING DEVICE.

Application filed December 5, 1923. Serial No. 678,604.

To all whom it may concern:

Be it known that I, SIGMUND L. GOLDMAN, a citizen of the United States, residing at Chicago, in the county of Cook and State 5 of Illinois, have invented a new and useful Improvement in Gas-Venting Devices, of which the following is a specification.

My invention relates, more particularly, to devices through which gas generated in a 10 chamber, as, for example, a keg, in the production of certain liquids, particularly through fermentation, is vented.

As to one feature of my invention, it relates to a novel and simple construction of 15 bung through which the gas is permitted to escape; and as to another feature it relates to the conducting of the gas away from the chamber, while avoiding the entry of air or other fluid into the chamber and which 20 would contaminate the contents thereof.

One of my objects is to provide a novel and simple construction of gas-venting bung which shall be adapted to be positioned in bung openings of kegs and the like, of different sizes and which shall effectively operate to serve as a gas vent in connection with these different sizes of receptacles, even when the latter are almost completely filled with the liquid undergoing treatment. Another 25 object is to provide a gas-venting bung which may be driven into position in the bung hole, without danger of breaking the gas-conducting tube associated therewith. Another object is to provide a novel and 30 simple construction of air-venting device whereby the gas may readily flow therethrough to exhaust and by which reverse flow through the gas passage will be prevented; and other objects are to generally 35 improve upon structures of the character 40 above referred to.

Referring to the accompanying drawing, the figure therein illustrated is a view in longitudinal sectional elevation through the bung opening portion of a barrel, this bung opening being equipped with a gas-venting device, also shown in sectional elevation and embodying my improvements.

The bung portion of the device is represented at 2, this bung, which may be of wood or any other suitable material, being of frusto-conical form, as shown, to seat in the tapered bung opening 3 shown as provided in the side wall 4 of a keg containing the fluid, represented at 5 and from which the gas to be conducted out of the keg is emit-

ted. The bung 2 is shown as provided with a passage 6 extending entirely lengthwise therethrough, the lower end of this passage opening through the bottom of the bung, and the upper portion of this passage being expanded to cause it to flare outwardly as represented at 7. The bung 2 also contains at its lower end a cross passage 8 intersecting the passage 6 and opening at its opposite 65 ends through the side of the bung.

Cooperating with the bung 2 is a gas-venting pipe 9 positioned at its lower end in a stopper 10 shown as of frusto conical form and preferably formed of cork, this stopper fitting into the upwardly opening portion 7 of the passage in the bung. The upper end of the tube 9 is turned downwardly to present the portion 11 which extends through a rubber stopper 12 confined in the mouth of a bottle 13 into the interior of which latter the lower open end of the portion 11 of the tube opens. The stopper 12 is provided with a vent-opening 14, and the lower open end of the portion 11 of the tube cooperates with a float 15 shown as formed of a generally spherical lower end portion 16 and an upwardly-extending shank portion 17 tapering upwardly, at which portion it extends into the lower end of the portion 11 of the tube, the bottle 13 containing any suitable liquid, as, for example, water, represented at 18 which extends above the lower open end of the portion 11 of the tube.

Assuming the gas venting device to be applied to a keg in the position shown in the drawings, the gas generated by the fermenting liquid 5 rises through the passage 6 in the bung and through the pipe 9, as for example of aluminum or glass, discharging from the lower end of the portion 11 thereof into the water 18 and thence passing outwardly to the atmosphere through the vent 14 in the stopper 12, the gas, in its movement forcing the check-valve 15 downwardly against the buoying action of the liquid 18. Inasmuch as the liquid 18 exerts a buoying action on the valve 15, back-siphoning of the liquid 18 into the tube 9 is positively prevented should the pressure in the keg above 100 the level of the liquid 5 for any reason become reduced below atmospheric pressure.

The provision of the device in separable parts permits the stopper equipped tube 9 to be preliminarily disconnected from the bung 2 which latter may then be driven into the bung hole 3 by striking it with

the desired force, thereby eliminating any danger of breaking the tube leading from the bung, and when the stopper 10 is inserted into the bung tight fit is insured by 5 reason of the resilient character of the stopper.

The feature of providing the gas vent with two outlets one of which extends through the bottom of the bung and the 10 other through the side of the bung, is of advantage particularly in connection with the use of the bung with bung holes of different sizes. The bung 2 is shown in connection with a bung hole of relatively 15 large size in which case the lateral outlets of the gas passage in the bung extend close to the under surface of the wall of the keg in which the bung hole is located, thereby providing for the passage of the gas into 20 the bung even when the level of the fluid 5 therein extends to a relatively great height and covers the inlet opening through the lower end of the bung. Where the bung is used in a bung hole which is of relatively 25 small diameter, the lower surface of the bung would extend considerably higher than it does in the arrangement shown, even to such a height that the lateral inlets would be covered by the wall of the bung 30 hole 3, and the gas would be conducted from the space above the fluid 5 into the gas inlet opening through the bottom of the bung. The bung is thus adapted for use in connection with bung holes of different 35 diameters, even where the top of the fluid 5 extends closely adjacent to the under surface of the wall in which the opening 3 is located.

Furthermore it will be noted that the various 40 parts of the device are rendered adjustable relative to each other to accommodate the latter to the various conditions met in practice, and that these parts may be readily disassembled, in which condition 45 they occupy very small space, which is of particular advantage in shipping and storing, and may be readily assembled for use.

The feature of providing the stopper 12 is of especial advantage particularly as compared 50 with the screw cap commonly provided, in that assembly of the bottle and stopper may be readily effected by merely pressing these parts toward each other and a highly effective closure results.

55 The stem of the valve 15 is made relatively long, as shown, in order that it will not fall out of the tube when no water is in the bottle 13.

The feature of providing the separable 60 bung and stopper is of further advantage in that the stopper 10 is adapted to be fitted

into the mouths of different sized bottles, as for example from pint to five gallon bottles, and thus by separating the bung from the stopper 10, the gas-venting device may be 65 used with such bottles, whereby the device is adapted for application to kegs and bottles of different sizes.

While I have illustrated and described a particular construction embodying my invention, I do not wish to be understood as intending to limit it thereto as the same may be variously modified and altered without departing from the spirit of the invention.

What I claim as new, and desire to secure by Letters Patent, is:

1. A bung formed of a tapered body having continuously open ports for gas-venting, at its inner face and at the side of the 80 tapered portion of the body which extends below the inner side of the cask when the bung is applied to use.

2. In combination, a cask containing a bung-hole, and a bung having a tapered 85 body which fits in said hole, said body extending inwardly beyond the wall of said hole and having continuously open ports, for gas-venting, at its inner face and at the side of the tapered portion thereof 90 which extends inwardly beyond said wall.

3. In combination, a bung formed of a tapered body ported, for gas-venting, at its inner face and at the side of the tapered portion of the body which extends below 95 the inner side of the cask when the bung is applied to use, an expanded opening into which said ports open, a stopper seated in said opening, a gas-conducting pipe extending through said stopper, and means carried by the distal end of said pipe and into 100 which said end extends whereby to vent the gas therefrom and to prevent the reverse flow of contaminating fluids through said pipe.

105 4. A gas-venting device comprising a bung adapted to seat in a bung-hole in a receptacle to be vented and provided with a passage extending throughout its length and opening into the receptacle and forming 110 a continuously open port, and through its side with a cross passage forming a continuously open port communicating with said central port, whereby said ports will vent the gas when the liquid level in the 115 receptacle is below the opening of the central port, and said side port will vent the gas when the liquid level within the receptacle is above the opening of said central port.

SIGMUND L. GOLDMAN.
